FIG. 1

FIG. 2

FIG. 3

FIG. 6

FIG. 4

FIG. 5

FIG. 1 is a front perspective view of a preferred embodiment of a microwave oven, showing my new design; FIG. 2 is a front perspective view of a second embodiment thereof;

FIG. 3 is an elevational left side view of the microwave oven of FIG. 1;

FIG. 4 is a bottom view of the microwave oven of FIG. 2;

FIG. 5 is a bottom view of the microwave oven of FIG. 1; and

FIG. 6 is an elevational left side view of the microwave oven of FIG. 2.

It will be understood that the grill pattern illustrated over small areas of the recessed window areas in FIGS. 1 and 2 continues uniformly throughout such recessed window areas.

I claim:

The ornamental design for a microwave oven, as shown and described.
